UNITED STATES PATENT OFFICE.

RICHARD BARTHOLOMEW SMITH, OF NEW YORK, N. Y.

SHADOW-CLOCK.

No. 813,636.

Specification of Letters Patent.

Patented Feb. 27, 1906.

Application filed April 3, 1905. Serial No. 253,706.

To all whom it may concern:

Be it known that I, RICHARD BARTHOLOMEW SMITH, a subject of the King of Great Britain, and a resident of the city of New York, borough of Manhattan, in the county and State of New York, have invented a new and Improved Shadow-Clock, of which the following is a full, clear, and exact description.

10 My invention relates to clocks in which the shadow of the moving hands is cast upon some surface, it being especially applicable to the display of advertisements.

15 It consists in the various features and combinations hereinafter described and more particularly claimed.

20 Reference is to be had to the accompanying drawings, forming a part of this specification, in which similar characters of reference indicate corresponding parts in all the figures.

25 Figure 1 illustrates one application of my invention. Fig. 2 is a central section through one embodiment of my improved mechanism. Fig. 3 is a section taken on the line 3 3 of Fig. 2. Fig. 4 is an enlarged detail, in front elevation, of the hand-operating mechanism. Fig. 5 is a transverse section therethrough on the line 5 5 of Fig. 4. Fig. 6 is a detail in 30 front elevation of the mechanism for intermittently moving the multiple dial. Fig. 7 is a transverse section therethrough, and Fig. 8 shows a central section through another form of my invention.

35 In a suitable casing 10 is mounted clock mechanism A, which in Figs. 2 to 7 of the drawings is shown as comprising a going-train *a* and a striking-train *b*. Dividing the casing into two sections is a partition 11, through which is an opening containing a transparent panel or member 12, preferably 40 of glass, at the center of which is set a spindle 13. About this spindle are rotatably mounted transparent members 14 and 15, each provided with a toothed rim 16, which meshes with gears 17 and 18 upon the minute-spindle and hour-sleeve, respectively, of the going-train. Carried by the members 14 and 15, they being preferably painted upon the 45 glass, are opaque hour and minute hands 19.

50 Mounted in the partition 11 and projecting from one side thereof is a spindle 20, upon which may rotate a wheel or supporting

member 21, having a circular series of openings in which are set transparent dials 22. 55 About each of these dials is a series of characters 23, each corresponding in position and number to the hour-numerals of the ordinary clock and preferably forming different combinations of words constituting advertising 60 matter. Upon each dial, between the hour characters, may be located the usual minute-divisions, while within these circumferential characters may be placed appropriate advertising phrases. A pinion 24 of the striking-train 65 engages teeth upon the rim of the wheel 21, and rotating with the train is included a notched locking-plate 25 and the usual fly 26, having projecting from it a locking-pin 27. Fulcrumed adjacent to this portion of the 70 striking-train is a locking-lever 28, having projections 29 and 30, which may respectively engage the notch in the plate 25 and the pin 27. With the opposite extremity of the locking-lever co-operates a lever 31, movable in a plane substantially at right angles to the plane of movement of the locking-lever and having a fork which receives the outer extremity of an operating-lever 32. The inner end of this operating-lever may 75 contact with a series of pins situated about the periphery of a gear 33 of the striking-train. The springs of the going and striking trains being wound, the hands are advanced over the dial, which is in registration with the 80 opening through the partition 11 to indicate the time in the usual manner. At predetermined intervals, depending upon the spacing of the pins upon the gear 33, the striking-train will be released through the movement 90 of the lever system, securing an automatic intermittent rotation of the wheel 21 to bring the succeeding dial opposite the partition-opening.

95 In connection with the mechanism which has just been described means are provided for casting a shadow of the hands and dial characters upon a screen or other surface. For this purpose I have shown a source of light consisting of an incandescent lamp 34, 100 situated within the casing at one side of the transparent members and having between it and said members a condensing-lens 35. In alignment with the lamp, lens, and transparent members extending from an opening in 105 the side of the casing is a tube 36, containing

a suitable projecting lens or system 37. The circuit being closed, the light from the incandescent lamp passes through the lens 35 and the transparent members 14 and 15 and the 5 particular dial which is opposite these members and is thrown by the lens 37 upon the receiving-surface in a luminous circle. The opaque hands, dial characters, and inscription cut off the light-rays, causing a shadow 10 of these elements to be cast within the circle. It should be noted that the transparent hand and dial members, together with the lamp and lenses, are all at one side of the opaque elements of the clock mechanism, so that 15 there is nothing to break the shadow to be cast. This not only furnishes a convenient means for telling time, but also a conspicuous display for advertisements. As illustrated in Fig. 1, the casing (indicated at X) 20 is supported above a door by a bracket Y. The shadow-clock is thus cast upon the sidewalk in front of the door at Z, where it may be seen and the advertisement read by passers-by.

25 It will be apparent that the feature of the multiple dial may be dispensed with, and in Fig. 8 of the drawings I have shown a more simple and compact arrangement of my apparatus, which is adapted for domestic use 30 or as a night-clock, the shadow being cast upon the wall of a receiving-screen. Here the partition 11 is omitted, and the transparent panel 12 furnishes a support for the characters, and therefore constitutes the dial, as 35 well as receives the spindle 13. The striking-train is absent, and for the spur-gears 17 and 18, driven by the going-train, are substituted bevel-gears 38 and 39, which mesh with like-toothed rims 40 upon the peripheries of the 40 members 14 and 15. Otherwise the apparatus may be in a general way similar to that previously described and used in the same manner, save that it will usually be convenient to maintain the lamp-circuit normally 45 open and provide a switch by which it may be closed to allow an observation of the time.

Having thus described my invention, I claim as new and desire to secure by Letters Patent—

1. In an apparatus of the class described, a 50 going-train having a member provided with studs, another train including a fly and a notched locking-disk, a double-armed locking-lever provided with projections adapted to engage, respectively, with said locking-disk and with a projection on the fly, an operating-lever in the path of the projections on said member of the going-train, an intermediate lever operatively related to the aforesaid levers, condensing and projecting lenses, 55 a source of light, transparent time-indicating means intermediate of said lenses and actuated by the going-train, and a panel-carrier operating between the lenses and operated at intervals by the second-named train. 65

2. In an apparatus of the class described, condensing and projecting lenses, a source of light, a rotary toothed panel-carrier equipped with a plurality of transparent panels and arranged to present said panels successively between said lenses, transparent time-indicating disks operating between the lenses, a going-train adapted to operate said disks, said train including a member provided with studs, an operating-lever actuated by said 70 studs, another train geared to the toothed panel-carrier, said last-mentioned train including a locking-disk and a fly, a locking-lever having two members arranged to engage, respectively, with said locking-disk and the 75 fly of the last-mentioned train, and a lever intermediate of the operating and locking levers for releasing the train to operate the panel-carrier at intervals.

In testimony whereof I have signed my 80 name to this specification in the presence of two subscribing witnesses.

RICHARD BARTHOLOMEW SMITH.
